UNITED STATES PATENT OFFICE.

HORACE E. WOODS, OF ROCK ISLAND, ILLINOIS.

IMPROVEMENT IN GRATES FOR FURNACES.

Specification forming part of Letters Patent No. 222,432, dated December 9, 1879; application filed July 15, 1879.

To all whom it may concern:

Be it known that I, HORACE E. Woods, of Rock Island, in the county of Rock Island and State of Illinois, have invented certain new and useful Improvements in Grates for Furnaces for Locomotives, Engines, &c.; and I hereby declare the following to be a full, clear, and exact description thereof, which will enable others skilled in the art to which my invention appertains to make and use the same, reference being had to the accompanying drawings, which form a part hereof, and in which—

Figure 1 represents a plan view of a fire-box of a locomotive embodying my improved side bars for supporting the grate-bars, with part of the grate-bars removed. Fig. 2 represents a side elevation of the same, and Fig. 3 represents a perspective view of said side bars.

Like letters of reference indicate like parts. My improvements relate to that part of the fire-box or side bars which support the grate-bars.

Prior to my invention or improvement, as hereinafter described, the grate-bars in a locomotive fire-box were sustained above the ash-pit by means of angle-irons or side bars rigidly attached or riveted to and against the inner shell or wall of the fire-box. This method of rigidly securing the side bars that support the ends of the grate-bars to and against the inner shell or wall of the fire-box is objectionable, for the reason that it causes oxidation of the inner shell or wall of the fire-box, thereby requiring frequent renewals or repairs of said shell or wall.

The object of my invention is to obviate the objections named by providing the fire-box with removable side bars which will move and shake with and adapt themselves to the irregular motion or shaking of the grate-bars, and so that thereby the fire-box may be thoroughly cleaned of ashes, cinders, &c.

In constructing a fire-box similar to that for which Letters Patent were granted to me July 24, 1877, No. 193,586, I attach at the usual height, above the ash-pit K, a series of studs or brackets, *ff*, of suitable length, to the inner surface of the shell or wall *h* of the fire-box,

and upon which are placed the removable side bars, *E*, which are constructed of iron or other suitable material, in the form as shown, and of a length nearly equal to the length of the inner longitudinal shells or walls of the fire-box.

The side bars, *E*, are provided on their lower edges with notches *cc*, to allow the bars to ride upon said pins or brackets *ff*, and on their upper edges with notches or grooves *bb*, to receive the rounded ends or bearings of the grate-bars *D*.

When it is desired to use said side bars, *E*, in an ordinary fire-box not provided with the mud-chamber *l*, as shown and described in said Letters Patent, I bolt a series of brackets or supports to the inside or to the under side of the mud-ring of sufficient length to project into the fire-box, and so as to receive and support the side bars, *E*.

When the grate-bars are rocked or shaken by the action of the lever usually employed for that purpose a slight longitudinal reciprocating motion and lateral rocking motion is thereby imparted to the side bars, *E*, whereby ashes, cinders, &c., are prevented from lodging between the side bars, *E*, and the inner wall of the fire-box, the side bars yielding laterally thereto, and so as to permit the ashes and clinkers to fall between the wall of the fire-box and side bars and between the side bars and grate, thereby keeping the inner surface of the inner shell or wall of the fire-box free and clean and from contact with the side bars and preventing the usual oxidation thereof.

Having thus described the nature and object of my invention, what I claim as new, and desire to secure by Letters Patent, is—

In a fire-box, the combination, with its shell or wall, provided with the pins or brackets *ff* and grate-bars *D*, of the longitudinal reciprocating and lateral rocking side bars, *E*, provided with the notches or grooves *bb* and *cc*, substantially as and for the purpose specified.

HORACE E. WOODS.
